D. P. McLAUGHLIN

ELEVATOR CONTROL ATTACHMENT FOR TYPESETTING MACHINES

Filed Oct. 13, 1926

FIG. 3

INVENTOR.
DENIS P. McLAUGHLIN

BY *A. B. Bowman*
ATTORNEY

UNITED STATES PATENT OFFICE.

DENIS P. MC LAUGHLIN, OF SAN DIEGO, CALIFORNIA.

ELEVATOR-CONTROL ATTACHMENT FOR TYPESETTING MACHINES.

Application filed October 13, 1926. Serial No. 141,256.

My invention relates to attachments to be used in connection with the assembly elevator of type setting machines, such as the linotype, intertype, linograph, etc., which attachment is adapted to prevent the assembling elevator from being raised from its assembly position until the line delivery carriage has returned to its regular position on such machines, and the objects of my invention are: first, to provide an attachment which is readily applicable to type setting machines for preventing the raising of the assembly elevator until the line delivery carriage has returned to its regular position; second, to provide an attachment of this class which will relieve the operator from continually watching for the return of the line delivery carriage before raising the assembly elevator before setting another line; third, to provide an attachment of this class which will reduce to a minimum the mashing or breaking of the line delivery carriage while it is returning to its normal seating position, which happens when the assembly elevator is raised too soon or before the carriage locks; fourth, to provide an attachment of this class which reduces the operator's responsibility in operating the linotype or type setting machine; fifth, to provide an attachment of this class which facilitates the operation of the type setting machine, particularly when the operator is setting short measure, the elevator is often raised too quickly before the line delivery carriage returns, causing breakage of parts; sixth, to provide an attachment of this class which in operation does not in any way affect the normal operation of the machine except to facilitate its operation; seventh, to provide an attachment of this class which is applicable for the different types of type setting machines now in use without changing the construction thereof; eighth, to provide an attachment of this class which is so constructed that it will permit the return of the elevator if necessary before it reaches the first elevator position, and ninth, to provide an attachment of this class which is very simple and economical of construction, durable, easy to operate, efficient in its action, and which will not readily deteriorate or get out of order.

With these and other objects in view, as

will appear hereinafter, my invention consists of certain novel features of construction, combination and arrangement of parts and portions as will be hereinafter described in detail and particularly set forth in the appended claims, reference being had to the accompanying drawings and to the characters of reference thereon, which form a part of this application, in which:

Figure 1 is a front elevational view of a type setting machine (in this case I have shown a fragmentary view of a linotype machine) showing my attachment in operative position thereon; Fig. 2 is a sectional view of the machine and attachment through 2-2 of Fig. 1, and showing the attachment by dotted lines, positioned to lock the elevator down, and Fig. 3 is a sectional view through 3-3 of Fig. 1.

Similar characters of reference refer to similar parts and portions throughout the several views of the drawings.

The support 1, bolt 2, lever 3, roller 4, and cam member 5 constitute the principal parts and portions of my attachment.

The support 1 is rigidly secured to the assembly elevator support base plate A of the assembling elevator of the type setting machine by means of screws 1^a through a flat plate on the front upper portion of said support. Integrally connected with this plate is a rectangular shaped enclosure portion 1^b open at its upper and lower sides. Pivotaly mounted in this portion 1^b on the opposite side near the front upper side by means of a bolt 2 is the lever 3, which lever 3 is provided with a downwardly extending curved portion 3^a, the lower end of which is flat at 3^b, forming a flat engaging member adapted to engage the upper side of the bar B when said lever is in the position shown by dotted lines in Fig. 2 of the drawings.

It will be here noted that the lever 3 assumes this dotted line position by gravity because of its offset mounting. The upper end of the lever 3 and 3^a is curved, as best shown in Fig. 2 of the drawings, so that it extends around the reinforced portion of the elevator slide bar A, shown best in Fig. 2 of the drawings. Mounted upon the upper end of the portion 3^a is a roller member 4, which is adapted to revolve thereon. Above this roller 4 is the delivery slide bar C of the conven-

tional typesetting machine. Secured on the back face thereof, and extending below the same and adapted to engage the roller 4 is a cam member of sufficient length which is provided with a cam face on one side, so that when the slide bar C reciprocates backwardly and forwardly, it engages the roller 4 and shifts the lever 3 to the position shown by solid lines in Fig. 2 of the drawings, whereupon the elevator can be raised. This, however, only happens when the elevator is in its returned position so that the cam 5 engages the roller 4. When the slide bar moves forwardly, the lever assumes the position shown by dotted lines in Fig. 2 of the drawings by gravity and prevents the movement of the elevator upwardly.

It will be noted that the back side of the portion 3^a engages the inner side of the horizontal cross portion 1^c of the support 1 and serves as a stop when the lever 3 is in the position shown by dotted lines in Fig. 2 of the drawings, thus preventing the lever from dropping back too far so that it will not engage the cam 5 with the reciprocation motion of the bar C.

It will be noted that the portion B is followed out at B¹ and provided with a spring B² adapted to operate the hook member D. The lever portion 3^a tends to engage this hollowed out portion B¹ and wear on the same. In order to obviate this I have provided a plate 6 adapted to cover the hollow portion and spring at the position of the lever portion 3^b.

The operation is as follows:

When the operator is setting type from the keyboard, the mats assemble in what is called an assembling elevator. When the line is set, whether it be 4 ems or 42 ems, he raises the elevator which releases a catch having a clamp to hold the line, called the line of delivery carriage, thus causing the line to be transferred in a lateral direction to what is known as the first elevator. When the line of the delivery carriage moves a certain distance, it releases a hook allowing the assembly elevator to drop to its seating position ready for the operator to set another line, but before he can do so he must be sure and wait until the line of the delivery carriage has come back to its regular position by the cam action back of the machine before he raises the elevator again, all of which is the conventional manner of operation. With the attachment, hereinbefore described, when the assembling elevator is raised and the delivery carriage moves forwardly in a lateral direction, it releases the lever 3 on the face plate of the elevator, which slides against the back of the assembly elevator and as soon as the assembly elevator drops into its seating or assembly position, the lever 3 falls within the top back of the assembly box a slight distance, but not enough to interfere with the assembling of the

next line of matrices, thus preventing the assembly elevator from being raised until the line of the delivery carriage is returned to its normal position. When the assembling elevator is in place and the line of delivery carriage is in its normal position, the lever is in a neutral position, thus allowing the elevator to be moved upwardly, but when the line of delivery carriage moves the line of mats over toward the first elevator, the assembly elevator cannot be moved upwardly until the carriage comes back.

It will be noted that the attachment, as shown and disclosed herein, is in connection with the conventional linotype type setting machine, but it is applicable for the different makes of type setting machines now in use, and although I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a type setting machine having an assembly elevator and a delivery slide bar, a support rigidly secured to the base plate of the support for the assembly elevator of a type setting machine, a gravity actuated lever pivotally mounted on said support adapted to engage said elevator, stop means on said support for regulating the movement of said lever, a cam member secured on the delivery slide bar of the type setting machine adapted to engage one end of said lever for shifting its opposite end out of engagement with the elevator.

2. In a type setting machine having an assembly elevator and a delivery slide bar, a support rigidly secured to the base plate of the support for the assembly elevator of a type setting machine, and a gravity actuated lever pivotally mounted on said support adapted to engage said elevator, means for regulating the movement of said lever, a cam member secured on the delivery slide bar of the type setting machine adapted to engage one end of said lever for shifting its opposite end out of engagement with the elevator, and a roller positioned on said lever adapted to engage said cam member.

3. In a typesetting machine, a support secured to the front upper portion of the assembly elevator support base plate, said support having a rearwardly extending bridge portion, a lever pivotally mounted within said bridge portion, said lever provided with a downwardly extending curved portion, the lower end of which is adapted to engage the upper side of the assembly elevator, an up-

wardly extending portion extending over the rear portion of the elevator slide bar and terminating at a point adjacent the lower edge of the delivery slide bar, a cam member 5 secured to said delivery slide bar and extending downwardly and over the upper end of the lever and adapted to shift the lower end of said lever out of engagement with said

assembly elevator when said delivery slide bar is in normal position, in the operation of 10 said typesetting machine.

In testimony whereof, I have hereunto set my hand at San Diego, California, this 6th day of October, 1926.

DENIS P. McLAUGHLIN.
